UNITED STATES PATENT OFFICE.

WILLIAM L. PFEIFFER, OF ROCHESTER, NEW YORK, ASSIGNOR TO WILLIAM J. WÖERNER, OF ROCHESTER, NEW YORK.

DESIGN FOR A DISK WHEEL.

59,375.

Specification for Design.

Patented Oct. 11, 1921.

Application filed May 13, 1921. Serial No. 469,381. Term of patent 7 years.

To all whom it may concern:

Be it known that I, WILLIAM L. PFEIFFER, citizen of the United States, residing at Rochester, in the county of Monroe and State of New York, have invented a new, original, and ornamental Design for a Disk Wheel, of which the following is a specification, reference being had to the accompanying drawing, forming part thereof.

Figure 1 is a side elevation of my new and ornamental disk wheel.

Fig. 2 is a vertical sectional view of the same.

Fig. 3 is an end elevation of the same.

I claim:

The ornamental design for a disk wheel as shown.

In testimony whereof I affix my signature.

WILLIAM L. PFEIFFER.
